UNITED STATES PATENT OFFICE.

EDGAR S. ROSENBLATT, OF SAN FRANCISCO, CALIFORNIA.

COMBINED CIGARETTE AND MATCH BOX.

1,193,428.

Specification of Letters Patent.

Patented Aug. 1, 1916.

Application filed December 6, 1913. Serial No. 805,025.

To all whom it may concern:

Be it known that I, EDGAR STERN ROSENBLATT, a citizen of the United States, residing in the city of San Francisco, county of San Francisco, and State of California, have invented a certain new and useful Combined Cigarette and Match Box, of which the following is a specification.

This invention is a combined cigarette and match box, and the object of the invention is a container of the character specified adapted to jointly incase cigarettes, or similar articles, in a simple, compact and economical manner.

15 The inconvenience of carrying separate containers for matches and cigarettes has long been recognized, and numerous attempts have been made to overcome these disadvantages, but, so far as I am aware, 20 no receptacle has been produced which possesses sufficient merit to be commercially adopted.

The present invention embodies a cigarette box having substantially the customary 25 form of construction, its cover being adapted to receive a package of book matches which are, preferably, detachably secured therein and in a specially arranged manner, whereby the matches may be readily detached and used more expeditiously and 30 efficiently than in constructions of the prior art.

Another feature of the invention consists in a cigarette retaining means positioned 35 within the cover, the principal function of which is to operate in conjunction with the match retaining means to hold the cigarettes against displacement, which, because of the extra depth of the cover, would occur, were 40 it not for the employment of this means.

In the preferred form of the invention, this cigarette retaining means is, also, adapted to serve as a match retaining means, so that a package of book matches may be held 45 at either end of the cover, thereby rendering it equally accessible to either a right-hand or left-hand user.

Features of the invention, other than those specified, as well as the advantages thereof, 50 will appear from the hereinafter detailed description taken in conjunction with the drawings.

In the accompanying drawings, I have 55 illustrated different practical embodiments of the present invention, but the construc-

tions shown therein are to be understood as illustrative, only, and not as defining the limits of the invention.

Figure 1 is a perspective view of a box embodying the present invention, the same being shown partly open, and the book of matches in operative position in the cover thereof. Fig. 2 is a section taken through the cover of the form of invention illustrated in Fig. 1, the matches being omitted. The plane of the section is parallel to the pivoted side of the cover. Fig. 3 is an underneath plan of a box cover embodying another form of the invention, and Fig. 4 is a section taken through a box embodying the structural features illustrated in Fig. 3. This section is also taken in a plane parallel to the pivoted side of the cover, namely, on the line 4-4 of Fig. 3.

Referring to the drawings, A indicates a 75 box or receptacle of the type now in general use in the retailing of cigarettes. This box is provided with a cover B, hinged along one of its longitudinal sides to a like side of the box A. The box or receptacle A is adapted 80 to contain cigarettes neatly packed, so that the top of the top layer will be about even with the top edge of the box, and the cover B is adapted to be folded down over the receptacle A to close the same.

By the present invention, a package of 85 book matches is adapted to be passed within the cover of the box and held in place, either fixedly or removably, in such position as to be readily and conveniently accessible when 90 the cover B is thrown open.

In the form of the invention shown in Figs. 1 and 2 of the drawings, the package 95 of matches is detachably held in place by means of triangularly shaped engaging members C, C, which are preferably glued into the cover so as to extend across the corners thereof, and at such relative distance from the top of said cover as to allow of the binding of the book of matches being 100 inserted with its ends in frictional engagement between the top of the box and the under side of the engaging members C, C. In this form of the invention, the striking surface d', commonly provided on book 105 matches, is left free and accessible for striking the matches thereon.

In the form of the invention disclosed in Figs. 3 and 4, the principle embodied in the construction described in connection with 110

Figs. 1 and 2 is carried out. In this latter form, however, the means for detachably retaining the book matches are given an additional function, viz: the retaining of the cigarettes in the receptacle A against shifting or shaking about, which they would have a tendency to do, owing to the increased depth of the receptacle necessary to provide space for the insertion of the book of matches.

While it is not considered absolutely essential, to my invention, I prefer to provide match retaining means at either end of the cover B, whereby a book of matches may be inserted into said cover in two positions, the one wherein the matches face to the left being that preferable for cases wherein the user is right-handed, and the other position being preferable when the user is left-handed. Thus, the chief aim of the invention, to provide, above all things, maximum convenience, is carried out in this particular. It will be noted that the provision of the retaining devices at either end of the cover makes it possible to utilize them for other novel functions. As hereinbefore stated, this particular thought is carried out in the modification illustrated in Figs. 3 and 4, wherein the match engaging means C' extends across the ends of the cover but is cut away, as at c', to allow of ready access to the striking surface on the book of matches. The particular advantage of this construction will be apparent from Fig. 4, it being clear that, when the cover is closed down, the lower face of the match engaging means C' will form a flange across the ends of the box, and thereby preclude the cigarettes from becoming displaced in transit.

In handling the invention commercially, it is desirable, in some cases, to pack the matches at the same time as the cigarettes and seal the box, so that, when it is opened, the matches and cigarettes are in a convenient and readily accessible position; in other cases, however, manufacturers desire to dispense with the trouble of packing the matches and simply pack the boxes with cigarettes and provide, in the cover of said boxes, means for holding a package of book matches such as is presented to a customer upon the purchasing of cigarettes, cigars, and the like. In view of these differences of desirabilities, I have considered it desirable to illustrate boxes adaptable for each, or both, methods of dispensation.

A salient feature of the invention resides in the positioning of book matches within the cover of a cigarette box of the kind now in general use in such position that the matches thereof will extend longitudinally of the box and the striking surface transversely thereof. Moreover, it is particularly desirable to have this striking surface quite near the end of the box, so that, when

said box is being held in the open position generally adopted by smokers in removing cigarettes from a box, this position is such as to present the striking surface for the matches in a most convenient and accessible position. It will thus be seen that, when the box is opened and a cigarette removed therefrom, it is not necessary to twist the wrist around in order to place the match striking surface in a convenient position, but the free and easy position in which the box is normally held in the hand is that position wherein the match striking surface is most convenient.

In the accompanying drawings are shown several modified forms of my invention, and, in the foregoing specification, I have described these several forms. It will now be clear that the combined cigarette and match box of this invention may be made in several forms.

In Figs. 1, 2, 3, and 4, the cover of the box is, preferably, made a trifle deeper than is usual with the cigarette boxes now in use, although this is not absolutely essential as the depth of the box or cover need not be made greater than usual. In any case, the increased depth of the box is so trifling in its extent as to be unnoticeable, except on careful examination.

Having thus fully described the invention, what I claim as new and desire to secure by Letters Patent is:—

1. As a new article of manufacture, a combined cigarette and match box embodying a cigarette receptacle, a cover pivoted at one side thereof, and retaining means extending across one end of the interior of the cover and secured to the opposite sides of said cover and to the end of the cover adjacent which said means is positioned to provide rigid match-engaging means, whereby, when a package of book matches is positioned within the cover and in engagement with said retaining means, the matches will extend parallel to the pivoted side of the cover and the striking surface of the match package will extend at right angles thereto, said retaining means being cut away for a portion of its extent to expose the striking surface of the package.

2. As a new article of manufacture, a combined cigarette and match box embodying a cigarette receptacle, a cover pivoted along one edge thereof, retaining means positioned interiorly of the cover and at the ends thereof adjacent the pivoted side, whereby the retaining means at either end of the cover may maintain a package of book matches rigidly in position interiorly of the cover, with the matches extending parallel to the pivoted edge and the striking surface at right angles thereto, each of said retaining means being cut away for a portion of its extent to expose the striking surface of the

package, and said retaining means being conjointly operable to engage with the opposite ends of the cigarettes in the receptacle, when the cover is in closed position,
5 for the purpose of precluding displacement of the cigarettes.

In testimony whereof I have signed my

name to this specification in the presence of two subscribing witnesses.

EDGAR S. ROSENBLATT.
